UNITED STATES PATENT OFFICE

LAURENCE HERBERT PEARSON, OF NOTTINGHAM, ENGLAND

APPARATUS FOR THE ELECTRICAL TRANSMISSION OF SOUND FROM GRAMOPHONE RECORDS

Application filed November 3, 1928, Serial No. 316,919, and in Great Britain October 5, 1928.

This invention comprises improvements in or relating to apparatus for the electrical transmission of sound from gramophone records, the class of apparatus to which the invention has more particular reference being that wherein an electrical device known as a pick up or collector is attached to the gramophone tone arm and coacts with the record so as to induce in said pick up varying electrical impulses which are suitably amplified and conveyed to a loud speaker or equivalent reproducing instrument.

Apparatus of this kind is particularly suitable for use in cinemas and other places of amusement for supplying orchestral and other music.

According to the present invention apparatus is provided embodying a plurality of gramophone record turn-tables, an electrical pick up for coacting with each record, sound amplifying means, means for transmitting sound from the records of said turn-tables in succession and means whereby after the last record of a series has been completed re-transmission from the records in succession may be automatically recommenced or automatically stopped.

It is to be understood that in connection with apparatus functioning in accordance with the present invention means for superimposing one record upon another may also be incorporated but any known or desirable means for superimposing may be employed and such means per se constitute no part of the present invention.

A feature of the invention consists in the provision of relays and means whereby on manipulation of a unit control the relays are set for the records to be brought into operation in succession.

A further feature consists in the provision of a two-way electrical switch associated with the last or final record of the series and so arranged that in one position the switch functions to cause the records to be brought into operation in succession and in the same sequence as before whilst in the other position the switch functions to terminate transmission from the records.

For the purpose of more fully describing

the nature of this invention reference will now be made to the accompanying drawing wherein is shown a circuit diagram illustrating a convenient method of carrying out the invention.

In the particular embodiment illustrated, three gramophone turntables are indicated at G¹, G², G³, each of the tone arms TA¹, TA², TA³ associated therewith having detachably attached thereto an electrical pick up P¹, P², P³, included in the primary circuits of transformers T¹, T², T³, respectively. The record turntables are driven by independent electric motors M¹, M², M³.

Associated with each tone arm is a sliding contact TC¹, TC², TC³ which are adapted to be traversed between parallel guide bars B into and out of engagement with pairs of spaced contacts C¹, C², C³, said last named contacts being carried by an insulator which is adjustable length-wise of the bars B. Each of the said contacts C¹, C², C³, is so adjusted that the respective sliding contacts TC¹, TC², TC³, in traversing the bars B as the tone arms traverse the record bridge such contacts when transmission from the records is completed. The electrical current input terminals are indicated at I, a line switch being preferably included at IL, and MCS is a master switch which governs the current supply to the apparatus and is moved to the "on" or "off" position by selectively energizing and de-energizing the two relays CR¹, CR².

In operation, the master switch MCS is first closed (as shown in the diagram) by energizing relay CR¹. This may be accomplished by drawing the first tone arm TA¹ right back so as to cause the sliding contact TC¹ to engage and bridge a pair of fixed contacts SC, thus closing the circuit of relay CR¹.

Simultaneously with the closing of switch MCS consequent upon contact TC¹ bridging the contacts SC, relays RY¹ and RY³ are energized to attract their respective armature AR¹, AR². Associated with the relays RY¹, RY³ are respectively relays RY², RY⁴. The arrangement of these relays and armatures AR¹, AR² is such that the armatures, after being operated by one of the relays, will re-

100

main in such operative position even after the relay in question ceases to be energized. For this reason the armatures AR^1 , AR^2 are preferably balanced armatures.

5 The energization of the relays RY^1 , RY^2 and the operation of the armatures AR^1 , AR^2 thereby, as previously described, effects closure of contacts MS^1 , TS^2 , MS^3 , TS^4 and consequently by the simple operation of the contact TC^1 in the manner described the whole apparatus is electrically (as distinct from mechanically) set for starting.

15 Assuming that it is desired to transmit the sound from the three records in succession the records will preferably be first placed on each turntable and after the apparatus has been electrically set as before described each pick up will be brought into contact with its respective record. Then upon completion of 20 the circuit of the motor M^1 by closure of switch MSC transmission of sound from the first gramophone record is commenced, the pick up P^1 being located in the primary circuit of the transformer T^1 as previously explained and the secondary of such transformer being across potentiometer V^1 to thermionic valve VA^1 . As the tone arm TA^1 traverses the record of the first gramophone 25 the contact TC^1 moves along the guides B and when the end of the record is reached such contact bridges fixed contacts C^1 and thereby energizes relay RY^2 . The effect of energizing such relay is to attract the armature AR^1 and open contacts MS^1 and TS^2 and bring the 30 motor M^1 to rest. At the same time contacts MS^2 are closed and thereby complete the circuit of motor M^2 driving the second gramophone record and contacts TS^1 are closed which short the secondary of transformer T^1 35 and thereby prevent the transmission of further sound from the first record. By virtue of shorting the secondary of transformer T^1 the transmission of any slurring sounds is definitely avoided.

40 45 It will also be noticed that the armature AR^1 opens the contacts TS^2 which when closed short-circuit the secondary of transformer T^2 included in the circuit of the pick up P^2 of the gramophone G^2 and transmission 50 of sound from the record of such gramophone is thereby enabled, the said pick up being connected through transformer T^2 and potentiometer V^2 to valve VA^2 , it being understood that whilst the first gramophone was 55 in operation closure of contacts TS^2 and TS^4 prevented the transmission of sounds from the pick up P^2 , P^3 respectively and thereby avoided interruption such as would be occasioned if the pick ups were disturbed during the 60 transmission of sound from gramophone G^1 .

Upon completion of transmission of sound from the gramophone G^2 contact TC^2 sliding along the bridge B closes the contact C^2 and thereby operates relay RY^4 which attracts the armature AR^2 , opens the contacts MS^3 ,

65 TS^4 and thereby brings the motor M^2 to rest and opens the short circuit across the secondary of transformer T^2 , closes contact MS^4 and so completes the circuit of motor M^3 and at the same time closes contacts TC^3 to short-circuit the secondary of transformer T^2 and thereby prevent transmission of further sound from the pick up P^2 and the avoidance of undesirable noises due to slurring or other causes.

70 75 The pick up P^3 being in contact with the record of gramophone G^3 now transmits the sound from such record through the medium or thermionic valve VA^3 which is connected to a potentiometer V^3 included in the secondary circuit of transformer T^3 the primary of which is in series with the pick up P^3 . Upon completion of the transmission of sound from the record of gramophone G^3 the contacts C^3 are bridged. Associated in the circuit of such contacts is a two-way switch SSR . In one position, when in contact with the contact S , relay CR^2 is energized upon the contacts C^3 being bridged by the sliding contacts TC^3 and by virtue 80 of the armature associated with relays CR^1 , CR^2 being a balanced armature the previously made contact at MSC is broken and further transmission effectually stopped. If on the other hand the switch SSR is in contact with the contact R , retransmission from 85 gramophone G^1 will be commenced, assuming of course that the pick up of such gramophone has been previously moved back to the starting position, although not sufficiently far back for contact TC^1 to bridge contacts SC , it being appreciated that when the switch SSR is in contact with contact R completion 90 of the contacts C^3 by the sliding contact TC^3 forms the same function as closure of contacts SC by sliding contact TC^1 .

95 100 The contact S is preferably marked "Stop" and the contact R "Repeat" and when it is desired to repeat transmission the contact is moved to the position R and during the time that sound is being transmitted from the third gramophone record the first and second gramophones are adjusted to their starting position and if it is desired the records are 105 changed during this time.

110 115 In order to avoid the transmission of sound from the records before the turntables have obtained the desired speed of rotation governors may be associated with each motor, the arrangement being such that when the motor speed falls below a pre-determined 120 minimum a short-circuit is effected and transmission of sound thereby prevented. Conveniently the governor may function to short-circuit the transformer secondary circuit. By these means the transmission of slurring sounds during the time that the motor is initially gaining speed is definitely avoided and under no circumstances will sound be transmitted unless the speed of the motor assumes 125 130

and maintains the requisite predetermined minimum.

The purpose of the potentiometer V^1 , V^2 , V^3 is to control the volume output from each pick up and this provision enables different types of records to be handled satisfactorily. Moreover if sound from another independent record is being superimposed upon that produced by any one of the records brought into operation in sequence in the manner herein described the provision of the aforesaid potentiometer enables control of the superimposing effects to be obtained.

Although in the drawings only three records have been shown it is to be understood that any number may be provided, and in each case the arrangement as described herein is such that when sound is being transmitted from one record the electrical output circuit from the other records is shorted so that manipulation or movement of the pick ups associated with the other records will not interfere with the transmission from the record that is being played at any time. Again in each case the arrangement will be such that after transmission from a record has been completed the output circuit is immediately short-circuited so that no slurring noises or other noises which may arise subsequent to transmission are passed through the amplifier.

I claim:—

1. Apparatus for the electrical reproduction of sound from gramophone records comprising a plurality of turntables and driving motors therefor, an electric pick up for each turntable for coacting with each record, sound amplifying means, a pair of relays associated with each turntable other than the last of the series of turntables, balanced armatures adapted for operation by said relays, said relays controlling the motor circuits and output circuits of the pick ups associated with the several turntables, a pair of contacts associated with each turntable, a member moving in unison with the tone arm of each turntable and said member closing the respective contacts to operate the respective relays.

2. Apparatus for the electrical reproduction of sound from gramophone records comprising a plurality of turntables and driving motors therefor, an electric pick up for each turntable for coacting with each record, sound amplifying means, a pair of relays associated with each turntable other than the last of the series of turntables, balanced armatures adapted for operation by said relays, said relays controlling the motor circuits and output circuits of the pick ups associated with the several turntables, a unit switch associated with the first turntable, said switch operating the relays associated with each turntable, said relays actuating their respective balanced armatures to close the motor circuit of the first turntable and short-circuit

the output circuits from all the other turntables, a pair of contacts associated with each turntable, said contacts closed in turn by a member moving in unison with the turntable tone arm to complete the respective relay circuits and close the motor circuits and open the output circuits of the turntables in succession so that during the reproduction of sound from each record the output circuits of all the other records are short-circuited.

3. Apparatus for the electrical reproduction of sound from gramophone records comprising a plurality of turntables and driving motors therefor, an electric pick up for each turntable for coacting with each record, sound amplifying means, a pair of relays associated with each turntable other than the last of the series of turntables, balanced armatures adapted for operation by said relays, said relays controlling the motor circuits and output circuits of the pick ups associated with the several turntables, and a unit control switch associated with the tone arm of the first turntable, said switch operating the relays to close the motor circuit of such turntable and short-circuit the output from the pick ups of all the other turntables and a manually operable switch controlling the opening and closing of the motor circuit of the first turntable.
